UNITED STATES PATENT OFFICE.

WILLIAM W. DARROW, OF CHICAGO, ILLINOIS.

DOOR-OPENING MECHANISM FOR FREIGHT-CARS.

1,108,343.

Specification of Letters Patent. Patented Aug. 25, 1914.

Application filed June 27, 1913. Serial No. 776,155.

To all whom it may concern:

Be it known that I, WILLIAM W. DARROW, a citizen of the United States, and a resident of Chicago, county of Cook, and State of Illinois, have invented certain new and useful Improvements in Door-Opening Mechanism for Freight-Cars, of which I do declare the following to be a full, clear, and exact description.

10 The present invention has for its object to provide a simple and effective construction of mechanism whereby the initial opening of freight car doors may be effected, and the invention consists in the features of novelty hereinafter described, illustrated in the accompanying drawings and particularly pointed out in the claims at the end of this specification.

Figure 1 is a view in side elevation showing a portion of a freight car door and the left hand front post of the door jamb with my invention applied thereto, the door being shown in closed position. Fig. 2 is a view similar to Fig. 1, but showing the door 25 partially opened and the parts in correspondingly shifted position. Fig. 3 is a view in cross-section above the door-opening mechanism and looking downward. Fig. 4 is a view similar to Fig. 1, but showing a modified form of the invention. Fig. 5 is a view in cross-section on line 5—5 of Fig. 4. Fig. 6 is a view similar to Figs. 1 and 4, but showing a modified form of the invention. Fig. 7 is a view in cross section 35 on line 7—7 of Fig. 6.

Freight cars having sliding doors are ordinarily provided with wedging means whereby the doors may be forced tightly against the door openings as the doors are moved to closed position. These wedging means frequently so tightly hold the doors in closed position that the initial opening of the doors is effected with difficulty and for this reason crowbars or like instruments are often used to effect the initial opening of the door with consequent danger of marring the edge of the door and the post. But my improved invention, I am enabled to quickly effect the initial opening of the door, so that the door may thereafter be readily moved along its track from the front of the doorway of the car.

In the form of my invention illustrated in Figs. 1, 2 and 3, of the drawings, 1 designates the car door and 2 the door post at the left hand side of the door opening. Upon

the door post 1 is mounted a stop plate 4 consisting preferably of an angle bar that is attached to the door post and to the side wall of the car by means of through bolts 5. 60 The outer portion 4^a of the stop plate 4 extends beyond the door post, so as to overlap the door when in closed position, this outer portion 4^a being flared or turned outwardly to aid in guiding the door as it reaches its 65 closed position. Upon the door 1 and at a point opposite the stop plate 4 is mounted a plate 10 having outstanding annular lugs or bosses 11 and 11^a projecting from the face thereof. The bosses 11 and 11^a of the 70 plate 10 are formed with openings (preferably square) through which pass the through bolts 12 and 13 that pass also through the door and are provided upon their inner ends with retaining nuts 14. 75 Upon the plate 10 is mounted a sliding member 15 provided preferably with inwardly projecting guiding flanges 16 that overlap the sides of the plate 10. The member 15 is formed with elongated slots 17 and 80 17^a through which pass the bosses 11 and 11^a. The boss 11^a of the plate 10 passes through a circular opening formed in an operating lever 18 that is pivoted upon the boss 11^a. A washer 20 is preferably placed 85 between the head of the bolt 12 and the sliding member 15, and preferably a similar washer 21 is placed between the lever 18 and the head of the bolt 13. The rear portion 90 of the sliding member 15 is shallower than its forward portion and across this sliding member 15 extends the wall 23. The operating lever 18 will be of convenient length to have its lower or handle portion of convenient length to be readily manipulated by 95 the attendant, and the upper or shorter end of this lever is provided with a cam shaped end 25 adapted to engage with the transverse wall or projecting part 23 of the sliding member 15. When the parts are in 100 the position shown and the door is closed, the sliding member 15 will be in the retracted position illustrated in Fig. 1, and the operating lever 18 will hang in substantially vertical position. If now it is 105 desired to start the door open, the attendant will grasp the handle or lower end of the operating lever 18 and swing the lever in the direction of the arrow, Fig. 1. As the operating lever 18 is thus shifted, the 110 cam shaped end 25 of the operating lever will bear against the rear face of the trans-

verse wall 23 of the sliding member 15 and thereby cause the sliding member to press against the end 4^a of the stop plate 4, and as the sliding member 15 is shifted from the position shown in Fig. 1 to the position shown in Fig. 2, the door 2 will be pried open a short distance, thereby releasing the door from the binding action of its wedges. After the initial opening of the door has thus been effected, the attendant will release the operating lever, thereby permitting it to return to the normal position shown in Fig. 1 of the drawings, and when the door is closed, the contact of the sliding member 15 with the projecting portion 4^a of the slide 4 will shift the sliding member 15 from the position seen in Fig. 2, to the position seen in Fig. 1.

In the form of my invention illustrated in Figs. 4 and 5 of the drawings, the stop plate 4 is the same in construction as that hereinbefore described, and is similarly arranged at the left hand side of the door opening. In this form of the invention, I have shown a plate 10^a mounted upon the door and upon this plate 10^a is placed a sliding member 15^a having flanges 16^a that overlap the edges of the plate 10^a. The sliding member 15^a in this form of my invention, is formed with an elongated slot 17^a and through this slot projects a boss extending outwardly from the plate 10^a. Through this boss extends a through bolt 12^a that passes through the door and is provided at its inner end with a retaining nut, and a washer 20^a is placed between the head of the through bolt 12^a and the sliding member 15^a. Preferably, the right hand end of the plate 10^a is connected to the car door by a bolt 12^b having a retaining nut upon its inner end. The outer end of the sliding member 15^a is preferably formed with an annular boss 30 that projects through an elongated slot 31 formed in the upper end of the operating lever 18^a. A bolt or rivet 32 passes through the boss 30 at the outer end of the sliding member 15^a, this bolt (if a bolt be used) being furnished with a nut at its outer end. This bolt and slot connection between the operating lever and the sliding member permits the relative movement of the parts, as will hereinafter appear. Preferably, a washer 34 is placed between the nut or headed end of the bolt 32 and the operating lever 18^a. The operating lever 18^a is pivotally mounted upon a bolt 36 that passes through the perforated boss of the operating lever and through the door 1 of the car. Preferably, a washer 37 is placed between the head of the bolt 36 and the boss of the operating lever, and a retaining nut at the inner end of the bolt 36 will securely hold it in position upon the car door.

From the foregoing description, it will be

seen that if the car door be in closed position shown in Fig. 4, and the operating lever is shifted in the direction of the arrow, Fig. 4, the sliding member 15^a will be forced against the end portion 4^a of the stop plate 4 and the door will be initially opened as the operating lever and sliding member are shifted. When the operating lever 18^a is released, it will return to the vertical position seen in Fig. 4, the sliding member 15^a being also returned to normal position there shown.

In the form of my invention illustrated in Figs. 6 and 7 of the drawings, the door post 2 at the left hand side of the door opening in the car body is shown as provided with a small casting 40 secured thereto by bolts 40^a, this casting 40 having a passage-way 41 in which is mounted a sliding bolt or member 42. This sliding bolt or member 42 is provided at the end farthest from the door 1 with a head 43, and at its opposite end with a nut or collar 44 secured thereto. Preferably, the casting 40 is formed with a recess 45 to receive the nut or collar 44 when the sliding bolt or member 42 is in the position shown in Figs. 6 and 7 of the drawings. To the wall of the car, adjacent the headed end of the sliding bolt or member 42 is pivotally mounted the operating lever 18^b, this lever being preferably pivoted upon a boss 50 projecting outwardly from a plate 51 that is secured to the car wall by bolts 51^a secured to the adjacent part of the car wall. A bolt 53 passes through the boss 50 of the plate 51 and through the adjacent part of the car wall and between the head of this bolt 53, and the operating lever 18^b is interposed a washer 55 that retains the operating lever 18^b in position upon the boss 50 of the plate 51. The upper end of the operating lever 18^b is formed with a cam shaped portion 25^a adapted to engage the headed end 43 of the sliding bolt or member 42. Upon the edge of the car door at a point opposite the nut or collar 44 of the sliding bolt or member 42 is secured a stop plate 4^b, this plate 4^b being connected to the edge of the door by screws 58 or in any other convenient manner.

From the foregoing description, it will be seen that when the car door is in closed position, the parts will occupy the positions seen in Figs. 6 and 7 of the drawings. If now it is desired to effect the initial opening of the car door, the operating lever 18^b will be swung in the direction of the arrow, Fig. 6, thereby causing the sliding bolt or member 42 to bear against the stop plate 4^b and force the car door open a slight distance, as the sliding bolt or member 42 is moved inward by the operating lever.

It will be readily understood that the precise details of construction above set out

may be varied without departure from the scope of the invention.

Having thus described my invention what I claim as new and desire to secure by Letters Patent, is:—

1. The combination with a car door and its frame, of a stop plate mounted upon one of said parts, an operating lever pivotally mounted upon the other of said parts and a movable member intermediate said operating lever and said stop plate whereby the initial opening of the door may be effected.

2. The combination with a car door and its frame having an outwardly projecting post, of a stop plate having a free end extending across and beyond said post to guide the door, an operating lever pivotally mounted upon the door and a movable member intermediate said operating lever and said stop plate whereby the initial opening of the door may be effected.

3. The combination with a car door and its frame, of a stop plate mounted upon one of said parts, an operating lever pivotally mounted upon the other of said parts, a

movable member intermediate said operating lever and said plate and a plate whereon said intermediate member is slidably supported.

4. The combination with a car door and its frame, of a stop plate mounted upon one of said parts, an operating lever pivotally mounted upon the other of said parts, a slotted movable member intermediate said operating lever and said stop plate, and a plate whereon said movable member is supported, and a guide projecting from said plate through said movable member.

5. The combination with a car door and its frame, of a stop plate mounted upon one of said parts, an operating lever pivotally mounted upon the other of said parts and a movable member intermediate said operating lever and said stop plate, said movable member having an outwardly projecting part against which said operating lever will bear to shift said movable member.

WILLIAM W. DARROW.
